UNITED STATES PATENT OFFICE.

RUFUS KING, OF PLAINVILLE, MASSACHUSETTS, ASSIGNOR TO BUGBEE & NILES COMPANY, OF NORTH ATTLEBORO, MASSACHUSETTS.

BRACELET.

Application filed April 14, 1926. Serial No. 101,933.

This invention relates to certain new and useful improvements in bracelets and pertains more especially to bracelets of the expansible link type.

5 The primary object of the invention is to provide a bracelet which has improved means for slidably connecting the connector members or slides to the boxes.

10 A further object of the invention is to provide connecting means which prevents lateral movement of the slides or connectors relative to the boxes.

15 The invention still further aims to provide means of the type mentioned which is economical and simple and which permits of free expansible movement of the parts.

In the drawings:—

20 Figure 1 is a fragmentary bottom plan view, partly broken away and in section of the invention.

Figure 2 is a section on line 2—2 of Fig. 1.

25 Figure 3 is a section on line 3—3 of Fig. 1, and

Figure 4 is a perspective view of one of the connectors.

30 In proceeding in accordance with the present invention 1 designates the boxes, which are formed of metal of uniform cross-section shaped to have tops 2, bottoms 3 and ends 4 and 5, the sides being left open.

The bottom 3 is of less length than the top 2, and is closed by a continuation 6 of the end wall 5 being bent rearwardly to 35 overlap the free end of the bottom wall as designated at 7. The bottom 3 is further bent downwardly and outwardly adjacent its longitudinal marginal edges as at 8 to provide guideway or tracks 9.

40 The slides or connectors 10 are substantially U-shaped and have side arms 11, which are slidably received between the top and bottom of the box 1 and are flush with the side edges thereof.

45 The bottom edges of the side arms 11 of the connector are slidably received in the longitudinal tracks 9 formed on the bottom of the box 1. The tracks 9 form or constitute guides for the side arms 11 of the connector and hold the latter against movement laterally of the boxes, while at the same time they permit relative sliding of the box and

connector in a free manner. A coil spring 12 is interposed between the closed end 13 of the connector and the end 4 of the box, the continuation 6 of the top wall of the box being bent over the end 14 of the connector and rearwardly to engage the bottom 3 whereby to secure the connectors to the boxes. The continuation 6, as shown in Fig. 60 3 is disposed between the offset parts 8 and lies flush with the outer faces of the guideways 9. Thus the offsets act to not only afford guideways, but also a depression in which the continuation 6 is received. 65

The several parts of the invention can be easily assembled, since in assembling, the boxes are initially formed U-shaped and are subsequently, after introduction of the connectors thereto, bent to the position 70 shown in the drawings.

Having thus described my invention what I claim as new and desire to secure by Letters Patent is:—

1. A bracelet including boxes formed of 75 metal of uniform cross-section, having tops, bottoms and open sides, the bottoms being bent downwardly and outwardly at their sides to form shouldered guideways and spring tensioned connectors for the 80 boxes having sides set on edge and flush with the marginal edges of the tops and bottoms, the lower side edges of the connectors engaging in the guideways and against the shoulders thereof and the upper 85 side edges engaging the under faces of the box tops, and an end extension on each box extending through the adjacent connector and bent under and against the bottom thereof and disposed between the downwardly 90 bent portions of the bottom.

2. In a bracelet, boxes having tops, bottoms and ends, the bottoms having offset parts forming guides at their sides and providing a depression between the guides, 95 spring tensioned connectors in the boxes engaged with the guides, and an extension on one of the box ends extending through the adjacent connector and bent to engage in the depression of the bottom. 100

In testimony whereof I have signed my name to this specification.

RUFUS KING.
